UNITED STATES PATENT OFFICE.

EDWARD D. SCHMITT, OF BALTIMORE, MARYLAND, ASSIGNOR TO PURE FOOD PROCESS COMPANY, OF BALTIMORE, MARYLAND, A CORPORATION OF MARYLAND.

JAR-CAP.

1,075,125.

Specification of Letters Patent.

Patented Oct. 7, 1913.

Application filed May 10, 1912. Serial No. 696,528.

To all whom it may concern:

Be it known that I, EDWARD D. SCHMITT, a citizen of the United States, residing at Baltimore city, State of Maryland, have 5 invented certain new and useful Improvements in Jar-Caps, of which the following is a specification.

This invention relates to improvements in jar caps.

10 The object of the invention is to provide a cap adapted for use in sealing or capping jars in which food products or other contents are cooked, after being hermetically sealed. This necessitates the use of a hard 15 metal cap possessing such rigidity as will enable the flange of the cap to be tightly crimped or bent into locking engagement with the locking shoulder on the exterior of the jar.

20 The principal object of the present invention is to provide a construction wherein the cap or closure may be tightly locked to the jar, so as to hermetically seal the same, and to provide with such construction, a means whereby the seal lock may be 25 broken, so that the cap may thereafter be readily removed by hand.

The invention consists in the main, in 30 making the closure in two parts, one a closing member, and the other a securing member or rim, which locks the closing member in place and in providing the securing member or rim with an opening lever which operates with a peculiar construction of rim 35 whereby the lever may be readily manipulated to break the seal so that the rim may thereafter be removed to reach the contents of the vessel.

40 The many advantages of the invention will become apparent in the course of the following description.

Referring to the drawings,—Figure 1 is a perspective view showing the cap applied. Fig. 2 is a similar view, looking at the cap 45 from a different direction. Fig. 3 is a perspective view showing the opening lever in about the position it would assume at the beginning of the twisting operation. Fig. 4 is a perspective view showing the securing 50 rim torn almost through. Fig. 5 is a view showing the opening lever twisted entirely out of the securing rim, and the rim in position to be sprung off the jar. Fig. 6 is a vertical sectional view of the cap, applied 55 to the upper portion of a jar, and Fig. 7 is

a group view showing the various parts of the cap, the closing member being slightly broken away to more clearly show its shape in cross section.

Referring to the drawings, the numeral 1 60 designates the jar, provided interiorly and adjacent to the lip, with an inclined annular surface 2, a rounding bead 3 and an exterior locking shoulder 4.

The numeral 5 designates the cap, which 65 comprises a securing rim 6, a closing member 7 and a gasket 8 of rubber or other compressible material. The cap is made preferably of tin of heavy weight, and the securing rim is provided with a depending 70 flange 9, adapted to be crimped at intervals into locking contact with the locking shoulder 4, as indicated at 10. The closing member is formed with a solid top 11, and its edge is bent upwardly, laterally, and downward, to form an annular channel 12 for the reception of the gasket 8. The inner wall 13 of the channel inclines slightly inwardly from the upper edge of the channel portion, as shown more clearly in Figs. 6 75 and 7, so that when this member is in position on the jar it will rest snugly against the inclined surface 2 thereof, as shown in Fig. 6.

The outer wall 14 of the channel is of 80 such length as to properly confine the gasket 8 and the length of the wall of course may be varied, as the exigencies of the case 85 may require, to accommodate gaskets of different thicknesses.

90 The securing rim 6 is formed with an annular channel 15, which, in cross section, conforms generally to the upper part of the channel portion of the closing member, so that when the rim is forced down over the 95 closing member, the inner wall 16 of the channel portion of the rim will bear tightly against the wall 13 of the closing member. At one side of the channel portion of the rim, I provide an integral opening lever 17, 100 which extends toward the center of the closing member when the parts are assembled and in position on the jar. The inner wall of the channel portion of the rim adjacent to the base of the lever may be notched 105 out, providing notches 18, which extend almost to the top of the wall, as shown clearly in Figs. 2, 3 and 7. These notches terminate in points 19 and extend inwardly toward each other, for a purpose which will 110

become apparent in the description of the operation of removing the cap. The upper surface of the rim is provided with two cut-out portions 20 the notches preferably having straight parallel sides and terminating in points 21. These notches are inside the points of termination of the notches 18, and the outer wall of the channel portion of the securing rim is further provided with 10 two substantially vertical notches 22, which extend from a point near the upper edge of the channel wall to a point near the bottom thereof, and these notches, like the notches in the top of the channel portion, are preferably formed with parallel side edges and pointed ends 23, thus providing a structure which, for all purposes of secure holding, is an integral structure, well adapted for permanently holding the closing member in 20 place, and in no way interfering with the necessary crimping of the flange of the securing rim, while at the same time, a structure is provided wherein, by the manipulation of the lever 17, a considerable portion 25 of the securing rim may be torn away, thus leaving the rim in such condition that it can be readily sprung apart and the whole seal removed.

In operation, the lever is gripped, say by 30 the thumb and fore-finger, lifted and pushed toward the periphery of the cap and when the back of the lever, near the base, engages the point *a*, as a fulcrum (better shown in Fig. 3), a tearing twist will result, which 35 will twist the metal at the point *b* until it tears into the notches 20. Further movement of the lever will bring it to a position wherein the point *c* will act as a fulcrum for the next operation which will be a twisting 40 tear that will carry the lever and the integral portion of the rim, into the notches 22, after having ruptured the rim at the point *d* and the final downward twist will break the lever and its integral part of the 45 rim entirely out, leaving the cap in the condition as shown in Fig. 5. In this condition, obviously, the ruptured ends of the rim need only be forced apart sufficiently to disengage the crimped portion of the 50 flange 9, from the locking shoulder of the jar, when the jar cap may be removed.

The tearing out of the rim leaves the seal in a condition where it may be readily removed by a slight further manual operation. The construction is one wherein the 55 whole cap may be replaced, less of course the torn away portion, but this is found sufficient to make a very tight temporary seal which may be highly advantageous for 60 use when only a part of the contents of the bottle or jar has been used, and it is desired to preserve or keep fresh the remaining or unused portion.

In re-applying the cap for the temporary 65 seal, it will be at once seen that when the

parts are put in the position shown in Fig. 5, a downward pressure upon the whole cap will force it back into place upon the jar, due to the wedging tendency of the engagement between the inner surface of the inner wall of the securing rim with the surface of the inner wall of the closing member, thereby producing a temporary seal, the tightness of which will be in proportion to the pressure applied.

I have found in practice that it is a very different matter, if not entirely impossible to tear tin of heavy weight, with a straight tear, and I have therefore contrived the various notches and cut out portions in the securing rim, so that sufficient leverage is obtained to twist the solid portions of the rim apart between the notches, producing, as above suggested, a twisting tear, the effect of which will be readily understood and appreciated by those skilled in the art. I prefer to stiffen and strengthen the opening lever by providing a rib 24, which is pressed or indented from the under side to the upper side of the lever.

Having thus described my invention, what I claim is:

1. A jar cap having a closing member formed with a gasket holding channel adapted to receive the lip of the jar, a securing rim formed with a channel to receive the channel portion of the closing member, said securing rim being provided with an opening lever integral with the lower edge of the inner wall of the channel of the securing rim, by which a part of the securing rim may be twisted off to unlock the seal.

2. A jar cap having a closing member formed with a gasket holding channel to receive the lip of the jar and a securing rim formed with a channel adapted to receive the channel portion of the closing member, said securing rim being provided with notches between which the metal thereof is adapted to be twisted apart, and an opening lever integral with the lower edge of the inner wall of the securing rim whereby a portion of the rim may be twisted out between the notches for unlocking purposes.

3. A jar cap having a closing member formed with a gasket holding channel, the inner wall of which is inclined inwardly, and adapted to receive the lip of the jar, and a securing rim formed with a channel, the outer wall of which is extended to form a locking flange and the inner wall inclined to fit the inner inclined wall of the closing member, and an opening lever integral with the lower edge of the inner wall of the securing rim, by which part of the securing rim may be twisted off to unlock the seal.

4. A jar cap having a closing member formed with a gasket holding channel, the inner wall of which is inclined inwardly and adapted to receive the lip of the jar,

and a securing rim formed with a channel, the outer wall of which is extended to form a locking flange and the inner wall inclined to fit the inner wall of the closing member, 5 said rim being provided with notches between which the metal of the rim is adapted to be torn and an opening lever integral with the lower edge of the inner wall of the securing rim, whereby the rim between the 10 notches may be twisted apart for unlocking purposes.

5. A closure for jars or bottles comprising a closing member having an inner annular wall, a securing rim fitting over the annular wall of said closing member, and an 15 opening lever integral with the lower edge of the annular wall of the securing rim, and extending across the upper face of the closing member, wherewith a part of the securing rim may be twisted off to unlock the 20 seal.

6. A closure for jars or bottles comprising a closing member having an inner annular wall, a securing rim fitting over the annular wall of said closing member and provided with notches, and an opening lever integral with the lower edge of the inner wall of the securing rim and extending across the upper face of the closing member, 25 whereby the metal of the rim between the notches may be twisted apart for unlocking purposes.

7. A closure for jars or bottles comprising a closing member having an inner annu-

lar wall, a securing rim fitting over the annular wall of said closing member, said rim being provided with notches, and a stiffened opening lever integral with the lower edge of the inner annular wall of the securing member and extending across the upper face 40 of the closing member, whereby the metal of the securing rim between the notches may be twisted apart for unlocking purposes.

8. In a jar closure, the combination with a bottle or jar, having an exterior locking 45 surface, a cap comprising a closing member having an inner annular wall, a securing rim fitting over the inner annular wall of the closing member and having its outer wall extended to form locking engagement 50 with the locking surface of the bottle or jar and its inner wall in engagement with the inner wall of the closing member, said securing member being provided with notches between which the metal of the securing rim 55 is adapted to be twisted apart, said rim being provided with an opening lever integral with the lower edge of the inner wall of the securing rim, whereby the metal between the notches may be twisted apart for 60 unlocking purposes.

In testimony whereof I affix my signature in presence of two witnesses.
